DESIGN FOR A NEEDLE THREADER

Philipp Christ, East Orange, N. J., assignor to Aid Manufacturing Company, East Orange, N. J., a partnership of New Jersey

Application May 9, 1940, Serial No. 92,244

Term of patent 7 years

To all whom it may concern:

Be it known that I, Philipp Christ, a citizen of the United States, residing at East Orange, in the county of Essex and the State of New Jersey, have invented a new, original, and ornamental Design for a Needle Threader, of which the following is a specification, reference being had to the accompanying drawing, forming part thereof.

In the drawing:

Figure 1 is an end elevational view of a needle threader showing my new design.

Figure 2 is a side elevational view.

Figure 3 is a top plan view; and

Figure 4 is a perspective view thereof.

The bottom surface of the needle threader body is substantially plain, like the plunger-adjacent surface on the top thereof as viewed in Fig. 3.

I claim:

The ornamental design for a needle threader, as shown and described.

PHILIPP CHRIST.
